UNITED STATES PATENT OFFICE

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON END PORTIONS OF SHOES

Application filed June 17, 1929. Serial No. 371,493.

This invention relates to machines for operating upon end portions of shoes and is illustrated as embodied in a machine for working end portions of stitchdown shoe uppers into lasted position and for pressing outturned flanges thereof against projecting margins of soles. In various respects, however, the invention is not limited in its application to machines for use in operating upon stitchdown shoes.

By the term "stitchdown shoe" is meant, of course, that type of shoe in which the marginal portion of the upper is outturned and secured to a sole the margin of which projects beyond the last bottom. While the practice of different manufacturers varies in detail, stitchdown shoes may be considered generally as of three kinds, namely, single-sole, two-sole, and three-sole shoes. In the single-sole shoe, the margins of the upper, and lining, if any, are turned outwardly and secured to the margin of a single extension sole. In the two-sole shoe, the margins of the upper and lining are turned outwardly and secured to a thin extension sole, the upper and extension sole being then secured to a second extension sole, which is the outsole. In the three-sole shoe, the first sole is an insole which does not extend beyond the last bottom and is assembled on the last with the upper; the lining is lasted inwardly over the bottom of the insole; a middle sole or first extension sole is then applied to the last and the outturned upper is secured to the margin of the extension sole; and an outsole of the size of the extension sole is then applied to the shoe and secured to the upper and middle sole. In all of these shoes a welt strip is usually applied to the exposed surface of the outturned margin of the upper and secured by means, usually stitches, which go through the upper and single sole or through the upper and outsole if there is more than one sole. It is also usual to insert a toe box and counter between the upper and lining at the toe and heel respectively, which are treated as parts of the upper materials. The toe box is frequently of material which can be softened prior to the lasting operation and contains cementitious material which, upon harden-

ing after lasting, will hold the upper in lasted position to the projecting margin of the sole. Thermoplastic box toe material is extensively used in this work and is effective, after cooling, temporarily to hold the lasted upper materials in lasted position until they are permanently secured.

In lasting the toe portions of stitchdown shoes of whatever type, it is particularly desirable not only that the upper materials be shaped over the toe and into the angle between the side of the last and the projecting margin of the sole, but that the upper at the angle be tucked under the edge of the last or insole so that a definite crease will be formed into which the edge of the welt strip may be forced and which in the finished shoe will give an appearance similar to that of the welt crease of a welt shoe.

An important object of this invention is to provide a machine by the use of which such a welt crease may consistently and uniformly be obtained in stitchdown work.

Other objects of the invention are to provide improved means for effecting the tensioning of the upper materials in conjunction with the working of them into lasted position, to insure that the shoe will be properly positioned and maintained against displacement during the upper shaping operation and, without sacrificing any of the advantages of prior machines for this work such as that disclosed in application Serial No. 244,230, filed January 3, 1928, in the name of René E. Duplessis, to provide a machine which will be rapid and effective in operation and which will be more nearly automatic than prior machines for this work.

With these and other objects in view, the organization of the illustrated machine comprises a pair of end embracing wipers constructed and arranged for advancing and closing movements and a shoe bottom rest or support located below the wipers and of sufficient extent to support the forepart of a shoe bottom including the margin of the sole of a stitchdown shoe which extends beyond the last bottom, together with power-operated means for effecting relative movement of the wipers and support heightwise of the shoe to

effect the operation of working the upper over the end of the last and against the projecting margin of the sole. As illustrated, the wipers are arranged to be manually adjusted to 5 adapt them to embrace the toes of shoes of different sizes and power-operated means is provided to impart to the wipers a predetermined advancing and closing movement to force the lasted upper materials under the 10 edge of the last bottom, or under the insole in work in which the shoe is provided with an insole, said predetermined movement being timed to occur after such relative heightwise movement between the support and the wipers 15 has been effected that the edge of the wipers is in a plane slightly below the edge of the last bottom. As illustrated also, the predetermined advancing and closing movements of the wipers are effected positively and these 20 movements are adjustable so that the depth of the crease formed in the upper under the shoe bottom may be varied.

In the illustrated machine, furthermore, 25 novel means is provided for effectively tensioning the toe portion of the upper during the operation of the wipers in shaping the upper to the last, such means preferably acting at the corners of the toe and at the sides of the toe. As illustrated, separate clamps at the 30 corners and sides of the toe are provided, which clamps are operated during the relative heightwise movement of the wipers and support to clamp the margin of the upper against the lower surface of the wipers, the 35 upper being progressively withdrawn from between the clamps and wipers during said relative heightwise movement.

In order that the clamps may not interfere with the projecting margin of the sole 40 and with the pressing of the upper by the wipers against the projecting margin of the sole, means is provided in the illustrated machine for withdrawing the clamps from operative position at that time during said relative heightwise movement when the wipers and the sole are in proximity to each other, the clamps at the corners of the toe being moved bodily lengthwise of the shoe and the 45 clamps at the sides of the toe being swung outwardly away from the shoe to an inoperative position.

In order that the relative heightwise movement of the wipers and shoe support may be 50 fully effective to work the upper into lasted position and to prevent movement of the shoe and last in response to the advancing movement of the wipers to form the crease, improved means is provided to hold the last against endwise rearward movement. As illustrated, a member or abutment is provided for engaging the rear end of the shoe and the abutment is operated in conjunction with the 55 relative heightwise movement of the wipers to force it against the shoe. This force is 60 preferably applied yieldingly and provision

is made for setting the position of the abutment, with respect to the means by which force is applied to it, to adapt the machine to handle shoes of various lengths and to insure that substantially the same pressure will be applied to shoes of various sizes irrespective of their length. When the shoe is released from the illustrated machine, the abutment is automatically withdrawn from the shoe a sufficient distance to permit convenient removal of the shoe and provision is made to insure that the abutment, when its position is changed for another length of shoe, will be so set with respect to the new length of shoe that this distance between the shoe and upper will always obtain after the shoe is released by the machine. The abutment is preferably arranged to be carried by the sole support and to be adjustable with respect thereto in accordance with the spring and with the swing of the last without affecting the connection by which the abutment is operated to apply endwise pressure to the shoe.

These and other features of the invention, including various novel constructions and arrangements of parts, will appear more fully from the following detailed description when read in connection with the accompanying drawings and will be pointed out in the appended claims.

In the drawings,

Fig. 1 is a side elevation, partly in section, of a machine embodying the present invention;

Fig. 2 is a front elevation of the machine illustrating its duplex organization;

Fig. 3 is a plan view, partly in section, showing the wipers, the shoe support, and the upper clamping mechanism;

Fig. 4 is an enlarged longitudinal section of the upper portion of the machine;

Fig. 5 is a detail sectional view on the line V—V of Fig. 4;

Fig. 6 is a view showing the shoe support and a shoe in the machine and illustrating the position of the operating instrumentalities of the machine after the upper has been shaped to the toe and preliminary pressure applied to the outturned upper and the projecting margin of the sole;

Fig. 7 is an enlarged view similar to Fig. 6 showing the position of the wipers after their advancing and closing movement and after final pressure has been applied by the work support to force the outturned upper and the projecting margin of the sole against the wipers;

Fig. 8 is a perspective view, partly in section, showing the wipers and the upper clamping mechanism, the parts by which the clamping mechanism is supported and guided being omitted; and

Fig. 9 is a diagram illustrating the relative timing of the cams which operate the shoe support and the wipers.

The illustrated machine for shaping uppers over the end portions of stitchdown shoes, and particularly the toe ends of such shoes, comprises a base or frame 10 in which is mounted a main shaft 12. On the shaft 12 are mounted a gear 14 and a cam block 16, there being between the gear 14 and the cam block 16 a suitable form of half-revolution clutch for intermittently connecting the cam block to the gear. The gear 14 is connected by suitable reducing gearing to an electric motor 18 or other suitable source of power by which the gear 14 may be continuously driven at low speed. As shown in Fig. 2, the machine is preferably duplex, the gear 14 being common to the two sides of the machine and there being on the right-hand side of the machine a cam block similar to the cam block 16 for imparting movements to the operating instrumentalities on the right-hand side of the machine. The mechanism at the left-hand side of the machine will be particularly described, it being understood that the mechanism at the right-hand side of the machine is substantially a duplicate of that on the other side, except for reversal of parts, and is arranged for operation on a shoe for the opposite foot, for example a right shoe. As best shown in Fig. 4, a stop projection 20 on the clutch between the gear 14 and the cam block 16 engages a stop arm 22, said arm being pivoted at 24 and having a forward projection carrying a pin 26 which is slotted off on its front side. An upright bar 28 has an elongated notch 30 in its upper end engaging the pin 26 and at its lower end is pivoted at 32 to a treadle 34. The length of the notch 30 is such that lost motion between the bar 28 and the pin 26 is permitted during the preliminary depression of the treadle, the notch 30 engaging the pin 26 and lifting the arm 22 from the projection 20 to permit setting of the clutch only during the final depression. After the machine starts, the bar 28 is pushed forwardly by a suitable formation on the cam block 16 to free the notch 30 from the pin 26, allowing the stop arm 22 to drop back into position to stop the machine again after the cam block 16 has made half a revolution.

The clutch and driving mechanism above briefly described may be substantially similar to that disclosed in United States Letters Patent No. 1,674,085, granted June 19, 1928, on application of Ballard and Seely, to which reference may be had for further explanation of this part of the machine.

A bar 36 is forked at its rear end to embrace the shaft 12 upon which it is guided. Pivoted at 38 on the inner side of the bar 36 is a roll which engages a cam track 40 in the cam block 16 by which the bar is moved lengthwise. At its forward end the bar is pivoted at 42 to the joint of a toggle one link 44 of which is pivoted at 46 to a rod 48 upon the upper portion of which is threaded a nut 50. The rod 48 extends freely into a hole in the top of a plunger 52 which is mounted for reciprocation in a cylindrical member 54, the upward movement of the plunger being limited by a screw 56 extending into a slot in the side of the plunger 52. Beneath the plunger is a spring 58 which rests on a support mounted for adjustment to vary the tension of the spring by turning a conveniently arranged handle 59, as explained in the above-mentioned patent. The other link 60 of the toggle is pivoted to a block 62 (Fig. 4) mounted in a slot 64 in the lower end of a longitudinally movable shaft 66. To confine the block 62 in the slot 64 a strap 68 is passed around the end of the post 66 and secured thereto by a bolt 70. Between the upper end of the block 62 and the end of the slot 64 is a space to permit the shaft 66 to be adjusted relatively to the block 62, as will be explained. The shaft 66 is guided for movement in the frame 10 of the machine in a direction inclined upwardly and rearwardly with respect to the machine and at its upper end has a reduced portion 74 on which is pinned a block 76. On the top of the block 76, which is horizontal, a sole supporting plate 78 is mounted by dowel pins one of which is shown at 80. On the lower end of the block 76 is a screw 81 which engages a boss on the frame and adjustably determines the heightwise position of the block 76 and shoe support 78, such adjustment being permitted by the portion of the slot 64 above the block 62. Thus the normal position, heightwise of the shoe, of the plate 78 may be varied for different thicknesses of soles by turning the screw 81. The plate 78 corresponds substantially in size and shape to the forepart of a stitchdown shoe sole including the marginal extension thereof, and, in order to take care of large variations in shoe sizes, the plate 78 may be lifted off and a larger or smaller plate substituted to correspond to the size of shoe being treated.

In the forward portion of the block 76 is mounted a pin 82 which is held in place by a draw-bolt 84. The draw-bolt 84, however, need not be set up tightly enough to prevent turning of the pin 82 but only sufficiently to hold it frictionally against turning movement. To the pin 82 is pivoted at 86 a member 88 which can be swung laterally on the pin to correspond to the swing of the last. Through a depending portion 89 of the member 88 is threaded a screw 90 bearing against the block 76 and provided with a hand-wheel 92 which may be turned to vary the angular relation in a vertical plane of the member 88 to the sole support 78, this adjustment being to take care of the spring of the last. The member 88 (Fig. 5) is channeled at 94 to receive a sliding member 96 the upper surface of which is formed with rack teeth 98. The

slide 96 is channeled on its under side to receive a compression spring 100 which bears at its inner end against the member 88 and at its outer end against the slide 96, the spring tending to hold the slide 96 outwardly against a suitable stop 102.

Arranged to slide on the top of the member 88 is a carriage 104, said carriage having a portion which extends into the channel 94 and is provided with ribs 106 which engage corresponding grooves formed in the upper portions of the side walls of the channel 94, the lower face of the carriage being arranged just above the surface of the rack teeth 98 and in sliding relation thereto. A plunger 108 is mounted in the carriage 104 for limited movement perpendicularly to the rack bar 98 and has teeth on its lower surface to engage the rack teeth 98 and lock the carriage 104 to the slide 96. The plunger 108 is held depressed by a compression spring 110 the upper portion of which surrounds the stem of a headed pin 112 the head of which frictionally engages a stem 114 arranged for sliding movement through the carriage longitudinally of the shoe. On the inner end of the stem 114 is pivoted at 116 an abutment 118 which is adapted to engage the rear end of the shoe, the abutment 118 preferably having a cover 120 of yielding material to prevent marring of the shoe upper and also having, as shown in Fig. 3, projecting portions 122 which prevent lateral movement of the rear end of the shoe with respect to the abutment 118. Inward movement of the stem 114 with respect to the carriage 104 is limited by a lug 124 on the stem which engages the carriage, and the stem is frictionally held from accidental displacement by friction of the headed pin 112 thereon due to the pressure of the spring 110. In order that the position of the carriage 104 with respect to the rack bar 98 may be changed to accommodate different lengths of shoes, the plunger 108 may be lifted against the tension of the spring 110 to disengage its teeth from the rack teeth 98 by a hand-piece 126 which at its lower end is secured by a pin 128 to the plunger and is guided for vertical movement with respect to the carriage by a headed stud 130 engaging suitable vertical guideways in the carriage 104, a slot 132 in the carriage permitting vertical movement of the pin 128. When the stem 114 is in its rearward position, it lies over the hand-piece 126 so that the hand-piece cannot be lifted to release the teeth of the plunger 108 from the rack bar 98. If, however, the stem 114 is pushed inwardly of the machine, the hand-piece 126 is free to be lifted and the carriage 104 can be placed in any position along the rack teeth 98. In order to locate the abutment 118 in the proper position for operation upon a shoe of given length, the stem 114 is pushed forward, the hand-piece 126 lifted, and the carriage 104

moved outwardly a sufficient distance to admit the shoe, which is then placed in the machine as shown in Fig. 4. The carriage 104 is then moved inwardly toward the shoe until the abutment 118 touches the rear end of the shoe, the hand-piece 126 being then released to permit the carriage to be locked to the rack bar 98. In the operation of the machine the slide 96 is moved toward the shoe, causing the carriage 104 to move relatively to the stem 114 until a projection 134 on the carriage engages the abutment 118 and enables the carriage to apply pressure through the abutment to the shoe at a point heightwise of the shoe which is near the plane of the sole. When the carriage 104 is allowed to be moved back by its spring 110, there will, of course, be at the rear of the shoe between the shoe and the abutment a space equal to the amount of relative movement between the abutment and the carriage so that the shoe can be easily removed from the machine, but, since the carriage 104 cannot be reset for a different length of shoe without first pushing the stem 114 inwardly to release the handles 126, it is assured that the space between the shoe and abutment will always obtain when the shoe is released and that the pressure applied to the shoe by the abutment will not be excessive.

For moving the slide 96 to operate the abutment as described, a pulley 136 is mounted on a stud 138 fixed to the slide 96 and occupying a slot 140 in the member 88. The bight of a cable 142 is placed upon the pulley 136, each of the two runs of the cable being passed over an idle pulley 144 mounted on the depending portion 89 of the member 88 near its pivot 86 and the two ends of the cable being held in a clamp 146 which comprises two similar plates grooved to receive the cable and held together by a bolt 148. The clamp 146 is connected to an arm 150 of an angle lever by means of a yielding extensible connection which, as illustrated, comprises two identical U-shaped members 152 and 154 which have their ends reversely bent to form hooks. The members 152 and 154 are passed in opposite directions through a compression spring 156, the loop of one being engaged by the bolt 148 and the loop of the other being engaged by a pin 158 passing through the end of the arm 150, which is bifurcated. Also connected to the pin 158 is a treadle rod 160 which passes through the outer portion of the treadle lever 34 (Fig. 1) and has thereon between the treadle and a nut 162 on the end of the rod a compression spring 164 which is stiff enough to overcome the spring 100. Consequently, when the treadle is depressed the slide 96 will be moved toward the shoe through the spring 164. The arm 150 above mentioned is part of an angle lever the other arm 166 of which (Fig. 4) is pivoted by a pin 168 to the shaft 66. A link 130

170 is pivoted at 172 to a bracket fixed to the machine frame and has its lower end bifurcated to embrace the arm 166, the bifurcations being vertically slotted at 174 to receive a pin 176 fixed in the arm 166. During the initial depression of the treadle described, the angle lever 150, 166 will turn on the pin 168 as a fulcrum, the pin 176 then moving downwardly in the slots 174 and the carriage 104 will be moved toward the shoe to take up the lost motion between it and the abutment 118, the portion of the arm 166 at the rear of the pin 168 of course moving upwardly.

To each side of the rear end of the arm 166 is pivoted at 178 a sleeve 180 through which passes a rod 182 having stop nuts 184 on its lower end. On each rod 182 is threaded a nut 186 forming an adjustable stop between which and the sleeve 180 is a compression spring 188. The upper ends of the rods 182, 182 pass through a horseshoe-shaped plate 190 (Fig. 8) and each rod is threaded into an upright member 192 to which is secured at 194 a clamp 196 having a laterally extending portion directed toward the shoe and arranged to be under the projecting margin of the upper and to be over the projecting margin of the sole. The clamps 196, 196 are arranged at the corners of the toe 80 and by upward movement of the members 192 are operated to clamp the outwardly extending margin of the shoe upper at the corners of the toe against the lower surface of toe embracing wipers 200, 202 which, as shown in Figs. 4 and 8, embrace the shoe toe in a plane located above the shoe bottom. The lower position of the upper clamps is adjustable by means of a screw 204 threaded through the horseshoe-shaped plate 190 and engaging a flat surface on the frame 10, the adjustment being such that the lateral projections of the clamps 196 are just above the projecting margin of the sole. The members 192 (Figs. 3 and 8) are guided on their inner faces by flat surfaces formed on projections 206 of the block 76 carrying the shoe support and on their outer faces are guided by rearwardly projecting portions 208 of plates 210 fixedly secured to opposite sides of the block 76. This construction enables the members 192 to be moved toward and from the shoe lengthwise thereof to carry the corner clamps 196, 196 into and out of upper clamping position, such movement being permitted, of course, by swinging movement of the rods 182 about their pivot 178 to the lever arm 166. Each of the plates 210 is provided with two ears 212 (Fig. 2) in which is mounted a vertical stem 214 (Fig. 8) the lower end of which rests on the horseshoe-shaped plate 190 and the upper end of which has an offset portion 216 to which a side clamp 218 is secured at 220. By turning movement of the stems 214, therefore, the clamps 218 may be swung laterally of the shoe toe into and out of po-

sition to clamp the upper against the wipers 200, 202.

In order to swing the side clamps 218, 218 outwardly of the shoe and to move the corner clamps 196, 196 bodily lengthwise of the shoe, the following mechanism is provided: On each of the stems 214 is an arm 222 to which is pivoted at 224 a block 225 having ears 226 to which is pivoted at 227 a link comprising two members 228, 229 which are threaded together so that lengthwise adjustment of the link may be effected. The rear end of the link 228, 229 is pivoted at 230 to a member 232 fixed to a horizontal rod 234, this rod passing through holes formed in the members 192 which carry the corner clamps 196. The central portion of the rod 234 passes through a yoke 236 into which is threaded a link 238 (Fig. 4) the rear end of the link being pivoted at 240 to a lever 242 fulcrumed at 244 on the machine frame and pivotally connected at its lower end to the toggle actuating bar 36. In order that the rectilinear movement of the bar 36 may be utilized to impart movement to the lever 242, a forked member 246 is pivoted to an ear 248 on the bar 36 and has a stem 250 which slides freely in a hole bored lengthwise of the lever 242. By the mechanism described it will be apparent that forward movement of the bar 36 will move the corner clamps 196 away from the shoe and will swing the side clamps 218 outwardly about the stems 214 away from the sides of the shoe, the clamps being thus moved out of position to clamp the upper against the wipers and their lateral extensions being consequently removed from position over the projecting margin of the sole so that the wipers and the shoe support may be relatively operated to press the outturned margin of the upper and the projecting margin of the sole together.

The wipers 200, 202 (Fig. 3) which embrace the end of the shoe are each detachably secured at 251 to a wiper carrier 252. Each wiper carrier is provided with two arcuate slots 254 which engage rolls 256 mounted on fixed axes in the wiper head 258, the slots 254 being so formed and arranged that when the wiper carriers are moved toward the shoe the wipers 200, 202 will be advanced and closed about a point 260 located substantially at the end of the toe where the wiping edges of the wipers meet. A cover-plate 261 (Fig. 1) is bolted to the head 258 to hold the wiper carriers 252 in place and to withstand the upward pressure on the wipers 200, 202. There are also blocks 263 secured between the cover-plate 261 and the head 258 which extend inwardly over the ends of the wipers 200, 202 and sustain them against upward pressure.

Two separate means are provided for effecting advancing and closing movements of the wipers, one being a manually effected adjustment for the purpose of setting the wipers 130

so that they will correspond to the shape and size of the toe of a shoe being lasted and the other being a power-effected movement of predetermined extent to cause the wipers to tuck the fold of the outturned upper under the edge of the last. Each wiper carrier 252 is connected at 262 to a link 264 the rear ends of the links 264 being pivoted at 266 to a cross-bar 268 having a rearwardly extending threaded stem 270. The stem 270 is threaded into a sleeve 272 which is mounted for rotating movement in a boss 274 formed on the wiper head 258 and is held from rearward movement by a flange 276. The rear end of the sleeve 272 is formed as a threaded stem 278 on which is threaded a hand-wheel 280, the hand-wheel being normally fixed to the stem by means of a set-nut 282. Between the hand-wheel and the boss 274 is a compression spring 284. It will be seen that by turning the hand-wheel 280 the sleeve 272 may be turned and the bar 268 moved forwardly or rearwardly to adjust the wiper carriers and hence the setting of the wipers 200, 202; that is, the extent to which they are initially advanced and closed, or retracted and opened, may be varied. The power-effected advancing and closing movement of the wipers is caused by pressure applied to the rear end of the stem 278 by an adjustable screw 286 threaded through the upper end of a lever 288 (Fig. 4) fulcrumed at 244 and having a roll 290 on its depending arm arranged to engage an edge cam 292 on the cam block 16. The screw 286 affords means for varying the effective upper tucking or crease forming movement of the wipers. The timing of the cam 292, as shown in Fig. 9, is such that the wipers are advanced and closed positively a predetermined amount after initial upward pressure has been applied to the work support 78 by the cam 40, acting through the toggle 44, 60, to press the outturned margin of the upper and the projecting margin of the sole against the wipers and prior to the final pressure applied by the cam 40 to the work support.

In order to clamp the upper to the last in the vicinity of the tip line to prevent undue movement of the upper relatively to the last by the tension applied to the upper, such as might result in forward bowing of the tip seam, a toe clamp 294 is provided, the clamp being preferably padded with yielding material 296 and provided with a cover 298 of leather or the like material. The clamp 294 has a stem 300 arranged to slide through a sleeve 302 (Figs. 1 and 2) clamped by a bolt 304 to a bracket 306 rigidly secured to the wiper head 258. Between the sleeve 302 and the clamp 294 is a compression spring 308 which resists upward movement of the clamp. Downward movement of the stem 300 is prevented by a screw 310 which passes through a washer engaging the sleeve 302. Rotation

of the stem is prevented by a screw 312 having a flattened end engaging a groove in the stem 300. The position of the clamp 294 longitudinally of the shoe may be varied by loosening the bolt 304, turning the sleeve 302 on the bolt as an axis and tightening the bolt.

In the drawings the machine is illustrated as operating upon a stitchdown shoe which, when completed, will have three soles. It is to be understood, however, that the machine is equally well adapted for operating upon shoes of any of the three kinds hereinbefore referred to or variations thereof. At the time when the toe lasting operation is performed, the shoe comprises an insole *a* and a middle *b* or first extension sole *b* secured to a last *c* on which are assembled an upper *d* and lining *e*, the lining *e* having been wiped in and secured to the insole by cement prior to the attachment to the last of the middle sole *b*.

It is also a usual practice in some work to pull over both the upper and the lining and secure them temporarily to the insole by partially driven tacks before the middle sole is applied, the shoe being allowed to remain in this condition until the upper has set to the last. The upper is then released by pulling the tacks, the lining secured to the insole and the middle sole applied, the shoe being in this condition when it comes to the operator of the illustrated machine. It is also usual to insert a heated thermoplastic toe box *f* between the upper and lining just prior to the introduction of a shoe into the machine.

In the operation of the machine the operator will slide forwardly the stem 114 of the abutment 118 to release the hand-piece 126, will raise the plunger 108 and move the carriage 104 rearwardly far enough to admit the shoe, that is, of course, unless the carriage is already in that position. The forepart of the shoe bottom is then placed upon the support 78 with the end of the shoe against the wipers 200, 202, which are adjusted if necessary by means of the hand-wheel 280 to advance and close the wipers or to retract and open them until they fit the size of toe being operated upon. The carriage 104 will now be released by lifting the hand-piece 126 and moved toward the shoe until the abutment 118 engages the shoe. Since the stem 114 of the abutment engages the hand-piece 126 when it is raised, the operator cannot move the carriage toward the shoe far enough to take up the lost motion provided between the stem 114 and the carriage. If the operator finds that the swing of the last is such that the abutment will not engage the rear end of the shoe as it should, he will swing the member 88 on the pin 82 against the friction of the draw-bolt 90 until the abutment is properly located so that the rear end of the shoe will engage between the projections 122 on the abutment. This lateral swinging move-

ment of the carriage and member 88 can be effected without disturbing the connections for moving the slide 96 and carriage 104 toward the shoe, since the pulley 136 can turn as the member 88 is swung to permit one run of the cable 142 to lengthen as the other run shortens. Upon contact of the abutment with the shoe, the hand-piece 126 is released and the carriage 124 becomes locked to the slide 96 by the action of the spring 110 on the plunger 108.

If the operator finds that the carriage 104 is not adjusted heightwise in accordance with the spring of the last properly to engage the rear end of the sole while the forepart is in flat engagement with the support 78, he will operate the hand-wheel 92 to effect such adjustments, the member 88 then turning on its pivot 86 to the pin 82. This movement, however, does not materially affect the tension of the cable 142 because the idle pulleys 144 are pivoted near the pivot 86 of the member 88.

To move the slide 96 and the carriage 104 toward the shoe, the operator depresses the treadle 24 which acts through the rod 160 and the cable 142 to move the slide 96 and the carriage toward the shoe. During this movement the carriage 104 will move relatively to the abutment to take up the lost motion between the abutment and the carriage and to bring the projection 134 into position to engage the abutment 118 at a point heightwise of the shoe which is below the center of the rear end of the last, pressure at this point being effective to hold the shoe against the wipers at the toe. During this movement of the carriage 104 the lever 150, 166 has been turning on the pin 168 as a fulcrum while the pin 176 has moved downwardly in the slots 174 of the link 170. This movement of the angle lever, acting through the springs 188, has lifted the clamps 196, 218 sufficiently to engage the upper and press it lightly against the lower face of the wipers 200, 202. If the operator finds, upon inspection of the shoe, that the upper materials have not been properly positioned between the wipers and the clamps, or wishes to change the adjustment of the machine for any reason, the treadle may be released and the operation repeated. The manual operation performed by the treadle as described puts very little burden upon the operator since in this operation only the tension of the light spring 100 has to be overcome in moving the carriage 104 and the clamps 196, 218 raised into position to engage the upper without applying substantial pressure to the clamps through the springs 188 or to the abutment 118 through the spring 152. When the parts have been moved by the treadle into these positions, however, the added resistance of the springs 188 to movement of the treadle causes the spring 164 to yield slightly and the clutch to be tripped since the

initial movement of the treadle 34 has taken up the lost motion provided by the notch 30, so that the final depression of the treadle will lift the stop arm 22 and trip the clutch, power rotation of the cam block 16 then taking place. During the power operation of the machine, the bar 36 will be moved longitudinally forwardly of the machine by the action of the cam track 40, causing the toggle 44, 60 to be straightened. As the toggle is straightened, the space 72 above the block 62 will be first taken up and then the shaft 66 will begin to move upwardly. The pin 176, having been brought by the operation of the treadle to the bottom of the slot 174, now becomes the fulcrum of the angle lever 150, 166, and, as the shaft 66 carrying the shoe supports 78, 104 moves upwardly under power to effect relative heightwise wiping movement between the shoe and the wipers 200, 202, the tension of the springs 188 will be rapidly increased since the rear end of the lever 166 moves faster than its point of connection 168 to the shaft 66 to cause the upper to be clamped against the wipers more and more firmly as the wiping operation progresses. At the same time the arm 150 has moved downwardly about the pin 176 as a center to cause the abutment 118 to be pressed yieldingly against the rear end of the shoe 95 through the spring 156.

The faces of the clamps 196, 218 which engage the upper are preferably transversely undulated or corrugated, as shown in Fig. 8, to provide sufficient friction between the clamps and the wipers so that the upper will not slip until the desired tension has been applied thereto and yet will not hold the upper so that it cannot slip or to such an extent that there is danger of its being damaged. The side clamps 218 are substantially opposite the outer ends of the wipers and the wipers are relatively long, so that the tension produced by the clamps 218 will cause the upper to be drawn down tightly to the last just at the rear of the tip line. The clamps 196, being placed at the corners of the toe, effect longitudinal tensioning of the upper at each side of the longitudinal median line along which the upper was previously stretched in the pulling-over operation, if that operation was employed, and effect tensioning of those portions of the toe of the upper which receive less tension during the pulling-over operation, that is, the portions which, when the shoe was in pulled over condition, constituted the ears or folds of the upper formed in that operation at the corners of the toe.

During the upward movement of the shoe 125 support 78 the upper is clamped to the last in the vicinity of the tip line by upward pressure of the shoe against the yielding abutment 294. This clamping of the upper to the last during the wiping operation prevents the tip

line from being bowed forwardly by the tension applied to the upper.

It will be noted that the shaft 66 does not move vertically but at a small angle rearwardly and upwardly so that during the upward movement of the shaft there is a component of movement of the shoe support and shoe toward the wipers to enhance their wiping action. During the early part of the wiping operation, the lateral extensions of the clamps 196, 218 are positioned over the projecting margin of the middle sole *b* with their ends close to the last and hence must be moved outwardly of the shoe to permit the projecting margin of the sole to be pressed against the outturned margin of the upper. This is effected by the described movement of the bar 36 which operates the lever 242 to retract the corner clamps 196 and to swing the side clamps 218 outwardly so that by the time the first rise of the shoe-support-pressure-cam 40 is effective, as shown in Fig. 6, to apply preliminary pressure to the sole and upper flange between the support 78 and the wipers 200, 202, the clamps will be sufficiently withdrawn to clear the margin of the sole. During the movement of the clamps outwardly of the shoe, less and less of the area of their clamping faces is in engagement with the upper but at the same time the upward pressure on the clamps progressively increases so that the effective clamping action of the clamps is substantially constant during that portion of the upward movement of the support in which such action is desirable. It will be apparent from Fig. 6 that the wiping edges of the wipers are now in a plane slightly below the last bottom and substantially in the plane of the insole *d*. During the preliminary pressure dwell of the cam 40, as illustrated in Fig. 9, the wiper cam 292 operates through the lever 288 to advance and close the wipers by the action of which, as illustrated in Fig. 7, the upper is tucked at the angle between the side of the last and the projecting margin of the sole under the last bottom and against the edge face of the insole *b*. Since the advancing and closing movements of the wipers are positive and predetermined and the shoe is held against rearward endwise movement by the abutment 118 as well as by the toe clamp 294, this creasing of the upper or carrying of the fold of the upper under the last bottom will be consistently and uniformly effected independently of the operator. If, for any reason such as faulty adjustment of the machine, the wipers should engage the side of the last instead of passing under the last bottom during their predetermined power operation, the shoe can be forced rearwardly against the tension of the abutment spring 156 and breakage of the machine will consequently be avoided. When, in the case of a three-sole shoe, as illustrated, the wipers

are operated against the edge of the insole, the insole will yield sufficiently in response to the positive power operation of the wipers to permit the upper to be carried under the last bottom to the required extent. Of course, under conditions where the margin of the sole is beveled or shoulder channeled, or where the margin of the last bottom is beveled, the operation of the machine will be equally as effective as under the more difficult conditions described.

While the wipers are held in by the wiper cam 292, the second rise of the shoe-support-pressure-cam operates the toggle 44, 60 to apply final and maximum pressure to the shoe support to press the outturned flange of the upper and the projecting margin of the sole more firmly against the wipers and to set the crease formed in the upper. The cam block 16 having now made a half revolution, the machine stops with the shoe held under pressure. The amount of upward pressure of the shoe support is, of course, determined by the amount of compression of the spring 58, and the point in the cycle of the machine when the spring is brought into action may be varied to suit different conditions of work by adjustment of the nut 50 on the plunger 48, the initial tension of the spring 58 being controlled by turning the handle 59.

The shoe remains under pressure until the operator has similarly treated another shoe, for example a shoe for the opposite foot, by the mechanism at the right-hand side of the machine. Supposing a thermoplastic toe box to have been inserted between the upper and lining prior to the placing of the shoe in the machine, the toe box will, of course, have been shaped to the last with the upper and its margin laid against the projecting margin of the sole. While the shoe remains in the machine under pressure, the hot cementing materials with which the toe box is saturated have time to cool and the pressure exerted causes some of the materials to be squeezed out of the toe box and to cause adhesion of the toe box to the extension sole and to the upper so that when the shoe, after cooling, is released from the machine, the materials remain in lasted condition and the shoe is ready for the usual subsequent operations of attaching the upper to the extension sole by stitches or staples and for the application of an outsole and welt, the latter being placed snugly in the crease provided by the action of the wipers about the toe of the shoe, and the welt, upper, middle sole and outsole being secured together by stitches.

In order to release the shoe the operator again depresses the treadle 34, whereupon the parts are restored to initial position, the abutment 118 being pushed outwardly by the spring 100 acting on the slide 96 and therefore opening up a space at the

rear end of the shoe equal to the amount of lost motion between the abutment 118 and the carriage 104. Thus ample space is provided for the removal of the shoe and 5 for the introduction of another shoe of the same size without any adjustments being made. Of course if the next shoe to be placed in the machine is substantially larger or smaller than the first one, it will be obvious to 10 the operator that adjustment of the carriage 104 longitudinally of the shoe is necessary and its position on the rack 98 of the slide 96 will be changed in the manner described.

Having thus described my invention, what 15 I claim as new and desire to secure by Letters Patent of the United States is:

1. In a machine for shaping the end portion of a stitchdown shoe to its last, the combination of end embracing wipers constructed and arranged for advancing and closing movements, a shoe support adapted to support the projecting margin of a sole upon the last, means for effecting relative movement of the wipers and the support heightwise of 20 the shoe to shape the upper to the last, and means operative to effect advancing and closing movements of the wipers, said last-named means being constructed and arranged to initiate said advancing and closing movements substantially at the termination of said relative heightwise movement to force the upper in the angle between the side of the last and the projecting margin of the sole under the last bottom 25 while the outturned margin of the upper lies against the projecting margin of the sole.

2. In a machine for shaping the end portion of a stitchdown shoe to its last, the combination of end embracing wipers constructed and arranged for advancing and closing movements, means for positioning the wipers for engagement with the end portion of the shoe, a shoe support for sustaining the sole of the shoe including its projecting margin, means for effecting relative movement between the wipers and support heightwise of the shoe to shape the upper to the last, and means operating after said relative heightwise movement has terminated to advance 40 and close the wipers to carry the upper under the last bottom and into the angle between the side of the last and the projecting margin of the sole and under the last bottom.

3. In a machine for shaping the end portion of a stitchdown shoe to its last, the combination of end embracing wipers constructed and arranged for advancing and closing movements, manually operated means for adjusting the wipers to the end portion of the shoe, a shoe support to sustain the shoe and last including a projecting margin of a sole, means for effecting relative movement between the wipers and the support heightwise of the shoe to shape the upper to the last, 45 power-operated means for advancing and

closing the wipers, and means for applying pressure to the shoe upper materials between the wipers and the projecting margin of the sole on shoe support.

4. In a machine for shaping the end portion of a stitchdown shoe to its last, the combination of end embracing wipers constructed and arranged for advancing and closing movements, a shoe support adapted to support the shoe and last including a projecting margin of a sole, means for effecting relative movement of the wipers and support heightwise of the shoe to shape the upper to the last, and power means operating after termination of said relative heightwise movement to 70 advance and close the wipers to carry a predetermined amount of the upper materials under the last bottom along the line where they are turned outwardly, the remaining outturned portion of the upper materials lying against the projecting margin of the sole.

5. In a machine for shaping the end portion of a stitchdown shoe to its last, the combination of end embracing wipers constructed and arranged for advancing and closing movements, a shoe support adapted to support the shoe and last including the projecting margin of a sole, means for effecting relative movement of the wipers and support heightwise of the shoe to shape the upper to 75 the last, and power means operating at the termination of said relative heightwise movement for positively advancing and closing the wipers to carry the upper materials under the last bottom along the line where they are turned outwardly, the remaining portion of the upper materials lying against the projecting margin of the sole.

6. In a machine for shaping the toe portion of a stitchdown shoe to its last, the combination of end embracing wipers constructed and arranged for advancing and closing movements, a shoe support constructed and arranged to support a shoe including the projecting margin of the sole, means for advancing and closing the wipers to adapt them to the toe of the shoe being operated upon, means for effecting relative movement between the wipers and the shoe support heightwise of the shoe to shape the upper to the end of the last and into the angle between the side of the last and the projecting margin of the sole, means for effecting advancing and closing movement of the wipers to tuck the upper under the last bottom, and means acting after the wipers are thus advanced and closed to apply pressure to the sole and upper materials between the wipers and the shoe support.

7. In a machine for shaping the end portion of a stitchdown shoe to its last, the combination of end embracing wipers constructed and arranged for advancing and closing movements, a shoe support adapted to support the shoe and last including a projecting 125

margin of a sole, power-operated means for effecting relative movement of the wipers and support heightwise of the shoe to shape the upper to the last, and power-operated means acting after the termination of said relative heightwise movement for advancing and closing the wipers a predetermined amount to carry the upper under the last bottom along the line where it is turned outwardly, the outturned margin of the upper lying against the margin of the sole.

8. In a machine for shaping the end portion of a stitchdown shoe to its last, the combination of end embracing wipers constructed and arranged for advancing and closing movements, a shoe support adapted to support the shoe and last including the projecting margin of a sole, power-operated means for effecting relative movement between the wipers and support heightwise of the shoe to shape the upper to the end of the last and into the angle between the side of the last and the projecting margin of the sole, power-operated means acting at the termination of said relative heightwise movement for positively advancing and closing the wipers, and power-operated means acting after the wipers are advanced and closed for applying pressure to the outturned upper and the projecting margin of the sole between the wipers and the shoe support.

9. In a machine for shaping the end portion of a stitchdown shoe to its last, the combination of end embracing wipers constructed and arranged for advancing and closing movements, a shoe support adapted to support the shoe and last including a projecting margin of a sole, means for effecting relative movement of the wipers and support heightwise of the shoe to shape the upper to the last, and means operating after the termination of said relative heightwise movement for advancing and closing the wipers a predetermined amount to crease the upper under the last bottom while the remainder of the outturned upper lies in contact with the outwardly projecting margin of the sole.

10. In a machine for shaping the end portion of a stitchdown shoe upper to its last, the combination of end embracing wipers constructed and arranged for advancing and closing movements, a shoe support adapted to support the shoe and last including a projecting margin of the sole, means for effecting relative movement of the wipers and support heightwise of the shoe to shape the upper to the last, and power means operating after said relative heightwise movement has terminated to advance and close the wipers positively a predetermined amount to tuck the upper under the last bottom and to press the outturned margin of the upper against the projecting margin of the sole.

11. In a machine for shaping the end portion of a stitchdown shoe to its last, the com-

bination of end embracing wipers constructed and arranged for advancing and closing movements, a shoe support, means for effecting relative movement of the wipers and support heightwise of the shoe to shape the upper to the last and into the angle between the side of the last and the projecting margin of a sole for applying pressure to the shoe materials between the wipers and the support and for maintaining such pressure unaltered for a period, means operating during said period for advancing and closing the wipers, and means acting after said movement of the wipers for applying increased pressure to the shoe materials between the wipers and the support.

12. In a machine for shaping the end portion of a stitchdown shoe to its last, the combination end embracing wipers constructed and arranged for advancing and closing movements, means for positioning the wipers for engagement with the upper, a shoe support, power-operated means for effecting relative movement of the wipers and support heightwise of the shoe to shape the upper to the last and into the angle between the side of the last and the projecting margin of a sole for applying pressure to the shoe materials between the wipers and the support and for maintaining such pressure unaltered for a period, power means operating during said period for positively advancing and closing the wipers, and power-operated means acting after said movement of the wipers for applying increased pressure to the shoe materials between the wipers and the support.

13. In a machine for shaping the end portion of a stitchdown shoe to its last, the combination of end embracing wipers constructed and arranged for advancing and closing movements, a shoe support, a power-operated cam for effecting relative movement of the wipers and support heightwise of the shoe to shape the upper to the last and into the angle between the side of the last and the projecting margin of the sole, said cam having a dwell, and power-operated means acting during the dwell of the cam to advance and close the wipers positively a predetermined amount to tuck the upper under the last bottom, said cam acting after the wiper movements have occurred to apply pressure to the outturned upper materials and the projecting margin of the sole.

14. In a machine for operating on the end portions of stitchdown shoes, the combination of a support to receive the sole of a shoe attached to its last and to support the sole including the margin thereof which projects beyond the last bottom, a wiper support above said shoe support, a pair of end embracing wipers on said wiper support constructed and arranged for advancing and closing movements, a power-operated cam having

two rises and a dwell between them, one rise acting to effect relative movement heightwise of the shoe between the shoe support and the wipers to shape the upper to the last and to press the outturned margin of the upper against the projecting margin of the sole, means for forcing the shoe endwise toward the wipers during the shaping operation, and power-operated means for effecting predetermined advancing and closing movements of the wipers during the dwell of the cam, said other rise of the cam then acting to apply further pressure to the shoe materials between the wipers and the sole support.

15. In a machine for operating upon the end portions of stitchdown shoes, the combination of a support to receive the sole of a shoe attached to its last and to support the sole including the margin thereof which projects beyond the last bottom, a wiper support above said shoe support, a pair of end embracing wipers upon the wiper support constructed and arranged for advancing and closing movements, and power-operated means for effecting relative movements heightwise of the shoe between the shoe support and the wipers to effect shaping of the upper to the last and to press the outturned flange of the upper against the margin of the sole, for advancing and closing the wipers to tuck the upper under the last bottom into the angle between the side of the last and the projecting margin of the sole, and for holding the shoe toward the wipers during the operation of the wipers.

16. In a machine for operating on the end portions of stitchdown shoes, the combination of a support to receive the sole of a shoe attached to its last and to support the sole including the margin thereof which projects beyond the last bottom, a wiper support above said shoe support, a pair of end embracing wipers on said wiper support, power-operated means for effecting relative movement heightwise of the shoe between the shoe support and the wipers to shape the upper to the last, and power-operated means to apply pressure to the shoe materials between the wipers and the shoe support.

17. In a machine for operating on the end portions of stitchdown shoes, the combination of a support to receive the sole of a shoe attached to its last and to support the sole including the margin thereof which projects beyond the last bottom, a pair of end embracing wipers on said wiper support constructed and arranged for advancing and closing movements, means for effecting relative movement heightwise of the shoe between the shoe support and the wipers to shape the upper to the last, means for pressing the outturned flange of the upper against the projecting margin of the sole, means for effecting predetermined advancing and closing movements of the wipers to tuck the upper into the

angle between the side of the last and the projecting margin of the sole under the last bottom, and power-operated means for applying heavy pressure to the outturned portions of the upper materials and to the projecting margin of the sole.

18. In a machine for operating on the end portions of stitchdown shoes, the combination of a support to receive the sole of a shoe attached to its last and to support the sole including the projecting margin thereof which projects beyond the last bottom, a pair of end embracing wipers constructed and arranged for advancing and closing movements, means for effecting relative movement heightwise of the shoe between the shoe support and the wipers to shape the upper to the last, power-operated means for pressing the outturned flange of the upper against the projecting margin of the sole, means for varying the time in the cycle when said pressure will become effective, and power-operated means for effecting predetermined advancing and closing movements of the wipers to tuck the upper into the angle between the side of the last and the projecting margin of the sole under the last bottom.

19. In a machine for operating on the end portions of stitchdown shoes, the combination of a support to receive the sole of a shoe attached to its last and to support the sole including the margin thereof which projects beyond the last bottom, a pair of end embracing wipers constructed and arranged for advancing and closing movements, means for effecting relative movement heightwise of the shoe between the shoe support and the wipers to shape the upper to the last, means for pressing the outturned flange of the upper against the projecting margin of the sole, means for effecting predetermined advancing and closing movements of the wipers to tuck the upper into the angle between the side of the last and the projecting margin of the sole under the last bottom, power-operated means for applying further pressure to the outturned portions of the upper materials and to the projecting margin of the sole, and means for varying the time in the cycle when said further pressure will become effective.

20. In a machine for operating on the end portions of stitchdown shoes, the combination of a support to receive the sole of a shoe attached to its last and to support the sole including the margin thereof which projects beyond the last bottom, a pair of end embracing wipers constructed and arranged for advancing and closing movements, means for effecting relative movement heightwise of the shoe between the shoe support and the wipers to shape the upper to the last, means for pressing the outturned flange of the upper against the projecting margin of the sole, means for effecting predetermined advancing and closing movements of the wipers to tuck the upper into the angle between the side of the last and the projecting margin of the sole under the last bottom, power-operated means for applying further pressure to the outturned portions of the upper materials and to the projecting margin of the sole, and means for varying the time in the cycle when said further pressure will become effective.

- the upper into the angle between the side of the last and the projecting margin of the sole under the last bottom, power-operated means for applying further pressure to the outturned portions of the upper materials and to the projecting margin of the sole, means for varying the time in the cycle when said further pressure will become effective, and means for varying the amount of said pressure.
21. In a machine for shaping the end portion of a stitchdown shoe to its last, the combination of a support to receive the sole of a shoe on a last and to support the shoe including a projecting margin of the sole, a pair of end embracing wipers above said support, means for effecting relative movement heightwise of the shoe between the shoe support and the wipers, and means for pressing the shoe endwise against the wipers during the relative heightwise movement between the shoe and the wipers.
22. In a machine for shaping the end portion of a stitchdown shoe to its last, the combination of a support to receive the sole of a shoe on a last, a pair of end embracing wipers above said support, means for effecting relative movement heightwise of the shoe between the shoe support and wipers, and means for urging the shoe yieldingly endwise toward the wipers during the relative heightwise movement between the shoe and the wipers.
23. In a machine for shaping the end portion of a stitchdown shoe to its last, the combination of a support to receive the sole of a shoe on a last, a pair of end embracing wipers above said support, means for effecting relative movement heightwise of the shoe between the shoe support and the wipers, means for urging the shoe yieldingly endwise toward the wipers during the relative heightwise movement between the shoe and the wipers, and means for pressing the outturned margin of the upper against the margin of the sole.
24. In a machine for shaping the end portion of a stitchdown shoe to its last, the combination of a support to receive the sole of a shoe on a last and to sustain a projecting margin of the sole, a pair of end embracing wipers above said support, means for effecting relative movement heightwise of the shoe between the shoe support and the wipers, means for engaging the opposite end of the shoe to hold the shoe against the wipers, and power-operated means for applying pressure to the outturned upper and the projecting margin of the sole between the wipers and the shoe support.
25. In a machine for shaping the end portion of a stitchdown shoe to its last, the combination of wipers constructed and arranged to embrace the end of a shoe, a shoe support, means for effecting relative movement of the wipers and support heightwise of the shoe, and means operating during said relative movement for yieldingly pressing the shoe endwise against the wipers.
26. In a machine for shaping the end portion of a stitchdown shoe to its last, the combination of end embracing wipers, a shoe support, means for effecting relative movement between the wipers and the support heightwise of the shoe to shape the upper to the last, an abutment engaging the rear end of the shoe, said abutment being arranged for lateral swinging movement to correspond to the swing of the last, and means for moving the abutment toward the shoe, said means having connections to said abutment for moving it longitudinally of the shoe, said connections being constructed and arranged to permit lateral adjustment of the abutment without disturbing the connections.
27. In a machine for shaping the end portion of a stitchdown shoe to its last, the combination of a support to receive the sole of a shoe on its last and to support the shoe including the projecting margin of the sole which projects beyond the last bottom, a pair of end embracing wipers above said support, means for effecting relative movement heightwise of the shoe between the wipers and the support to shape the upper into the angle between the side of the last and the projecting margin of the sole and to press its outturned margin against the projecting margin of the sole, and an abutment engaging the opposite end of the shoe during said shaping operation.
28. In a machine for shaping the end portion of a stitchdown shoe to its last, the combination of a support to receive the sole of a shoe on its last and to support the sole including the margin thereof which projects beyond the last bottom, a wiper support above said shoe support, a pair of end embracing wipers on the wiper support, means for moving the shoe support heightwise of the shoe relatively to the wipers to cause the wipers to shape the upper to the last and to press its outturned flange against the projecting margin of the sole, and means for pressing the shoe endwise toward the wipers during the operation of the wipers.
29. In a machine for shaping the end portion of a stitchdown shoe upper to its last, the combination of a support to receive the sole of a shoe on its last and to support the sole including the margin thereof which projects beyond the last bottom, a wiper support above said shoe support, a pair of end embracing wipers on said support, power-operated means for effecting relative movement heightwise of the shoe between the shoe support and the wipers to shape the upper to the last and to press its outturned flange against the projecting margin of the sole, means for pressing the shoe toward the wipers during the operation of the wipers.

and power-operated means for applying heavy pressure to the materials between the wipers and the sole support.

30. In a machine for shaping the end portion of a stitchdown shoe upper to its last, the combination of wipers constructed and arranged to embrace the end of a shoe, a shoe support, means for effecting movement of the support heightwise of the shoe toward the wipers, and means carried by the support and operated during said movement of the support for yieldingly pressing the shoe endwise against the wipers.

31. In a machine for shaping the end portion of a stitchdown shoe upper to its last, the combination of a support to receive the sole of a shoe attached to its last including the margin of the sole which projects beyond the bottom of the last, a wiper support above the shoe support, a pair of end embracing wipers on the wiper support, power-operated means for effecting relative movement heightwise of the shoe between the shoe support and the wipers to shape the upper to the end of the last and against the projecting margin of the sole, an abutment engaging the opposite end of the shoe, and power-operated means for applying heavy pressure to force the outturned margin of the upper against the margin of the sole.

32. In a machine for shaping the end portion of a stitchdown shoe upper to its last, the combination of a support to receive the sole of a shoe on its last and to support the projecting margin of the sole, a wiper support above said shoe support, a pair of end embracing wipers on the support, means for effecting movement of the shoe support toward the wipers to cause the wipers to shape the upper to the toe of the last, an abutment engaging the rear end of the shoe, and means operated by said movement of the support for pressing the abutment toward the wipers to maintain the upper in wiping relation to the wipers during the upper shaping operation.

33. In a machine for shaping the end portion of a stitchdown shoe upper to its last, the combination of a support to receive the sole of a shoe attached to its last, a wiper support above said shoe support, a pair of end embracing wipers on the support, power-operated means for effecting relative movement heightwise of the shoe between the shoe support and the wipers to shape the upper to the end of the last, an abutment for engaging the opposite end of the shoe, means operated by said power-operated means to press the abutment endwise of the shoe toward the wipers during the operation of the wipers, and power-operated means for exerting heavy pressure upon the outturned flange of the upper and the margin of the sole between the wipers and the support.

34. In a machine for shaping the end por-

tion of a stitchdown shoe upper to its last, the combination of a support to receive the sole of a shoe on its last and to support the shoe including the projecting margin of the sole which projects beyond the last bottom, a pair of end embracing wipers above said support, means for effecting relative movement heightwise of the shoe between the wipers and the support to shape the upper into the angle between the side of the last and the projecting margin of the sole and to press its outturned margin against the projecting margin of the sole, an abutment engaging the opposite end of the shoe during said shaping operation, and means for moving the abutment away from the shoe to permit easy removal of the shoe after the shaping operation.

35. In a machine for shaping the end portion of a stitchdown shoe upper to its last, the combination of a support to receive the sole of a shoe on its last, a pair of end embracing wipers above the support, power-operated means for effecting movement of the support heightwise of the shoe toward the wipers to cause the wipers to shape the upper to the end of the last, an abutment engaging the opposite end of the shoe, a carriage for the abutment, said carriage and abutment having a lost-motion connection between them, manually operated means for moving the carriage toward the shoe to take up said lost motion, and means operated by said power-operated means for forcing the carriage toward the wipers.

36. In a machine for shaping the toe portion of a stitchdown shoe upper over its last, the combination of a support to receive the sole of a shoe on its last and to support the shoe including the margin of the sole which projects beyond the last bottom, a pair of end embracing wipers, an abutment normally spaced from the rear end of the shoe to permit introduction of the shoe, manually operated means to effect movement of the abutment toward the wipers to locate the abutment in operative relation to the rear end of the shoe, power-operated means for effecting relative movement heightwise of the shoe between the shoe support and the wipers to shape the upper to the last, means operated by said power-operated means for forcing the abutment toward the shoe during the relative heightwise movement between the wipers and the support, and means controlled by said manually operated means for setting the power means in operation.

37. In a machine for shaping the toe portion of a stitchdown shoe upper over its last, the combination of a support to receive the sole of a shoe on its last and to support the shoe including the margin of the sole which projects beyond the last bottom, a pair of end embracing wipers, an abutment normally spaced from the rear end of the shoe to permit

introduction of the shoe, manually operated means to effect movement of the abutment toward the wipers to locate the abutment in operative relation to the rear end of the shoe,

- 5 power-operated means for effecting relative movement heightwise of the shoe between the shoe support and the wipers to shape the upper to the last, and means operated by said power-operated means for forcing the abutment toward the shoe during the relative heightwise movement between the wipers and the support.

38. In a machine for shaping the end portion of a stitchdown shoe to its last, the combination of a support to receive the sole of a shoe attached to its last and to support the shoe including the margin of the sole which projects beyond the bottom of the last, a wiper support above said shoe support, a pair of end embracing wipers on the wiper support, power-operated means for effecting relative movement heightwise of the shoe between the shoe support and the wipers to shape the upper to the last and against the
- 25 projecting margin of the sole, an abutment for engaging the opposite end of the shoe, and means operated by said power means to apply pressure to the abutment endwise of the shoe to hold it against the wipers.

39. In a machine for shaping the end portion of a stitchdown shoe on its last, the combination of a support to receive the sole of a shoe attached to its last and to support the shoe including the margin of the sole which projects beyond the bottom of the last, a wiper support above said shoe support, a pair of end embracing wipers on the wiper support, power-operated means for effecting relative movement heightwise of the shoe between the shoe support and the wipers to shape the upper to the last and against the projecting margin of the sole, an abutment engaging the opposite end of the shoe, means operated by said power means to apply pressure to the abutment endwise of the shoe to hold it against the wipers, and power-operated means for applying heavy pressure between the wipers and the support to force the outturned margin of the upper against the
- 50 margin of the sole.

40. In a machine for shaping the toe portion of a stitchdown shoe to its last, the combination of a support to receive the sole of a shoe on its last, a wiper support above said shoe support, a pair of end embracing wipers on the wiper support, means for effecting movement of the shoe support toward the wipers to cause the wipers to shape the upper to the toe of the last, an abutment for engaging the rear end of the shoe, a carriage for the abutment, said carriage and abutment having a lost motion connection between them, and means operative as an incident to said movement of the support for moving the carriage toward the wipers to apply

pressure to the shoe to maintain the upper in wiping relation to the wipers during the upper shaping operation.

41. In a machine for shaping the toe portion of a stitchdown shoe upper to its last, the combination of a support to receive the sole of a shoe attached to its last, a wiper support above said shoe support, a pair of end embracing wipers on the wiper support, means for effecting movement of the support toward the wipers to cause the wipers to shape the upper to the toe of the last, a slide carried by said support and arranged for movement longitudinally of the shoe, a carriage adjustable relatively to the slide, an abutment for the rear end of the shoe mounted on said carriage and having a lost motion connection with the carriage, a spring for holding the slide away from the shoe and means operating during said movement of the support for moving the slide toward the wipers to apply pressure to the abutment to maintain the upper in wiping relation to the wipers during the upper shaping operation.

42. In a machine for shaping the end portion of a stitchdown shoe to its last the combination of end embracing wipers constructed and arranged for advancing and closing movements, a shoe support adapted to support the shoe including a projecting margin of the sole, means for effecting relative movement of the wipers and support heightwise of the shoe to shape the upper to the last, power-operated means acting after the termination of said relative heightwise movement for advancing and closing the wipers, an abutment for preventing endwise movement of the shoe in response to the advancing movement of the wipers, and means for moving the abutment toward the shoe in conjunction with the relative heightwise movement between the wipers and the support.

43. In a machine for shaping the end portion of a stitchdown shoe to its last, the combination of end embracing wipers constructed and arranged for advancing and closing movements, a shoe support, power-operated means for effecting relative movement between the wipers and support heightwise of the shoe to shape the upper to the end of the last and into the angle between the side of the last and the projecting margin of a sole, means acting at the termination of said relative heightwise movement for advancing and closing the wipers, means for holding the shoe from rearward movement during the advancing movement of the wipers, and power-operated means acting after the wipers are advanced and closed for applying pressure to the shoe materials between the wipers and the shoe support.

44. In a machine for shaping the end portion of a stitchdown shoe to its last, the combination of end embracing wipers constructed and arranged for advancing and closing,

movements, a shoe support, power-operated means for effecting relative movement of the wipers and support heightwise of the shoe to shape the upper to the last and into the angle between the side of the last and the projecting margin of a sole for applying pressure to the shoe materials between the wipers and the support and for maintaining such pressure unaltered for a period, means operating during said period for positively advancing and closing the wipers, means for holding the shoe against movement during said movements of the wipers, and means acting after said movement of the wipers for applying increased pressure to the shoe materials between the wipers and the support.

45. In a machine for shaping the end portion of a stitchdown shoe to its last, the combination of end embracing wipers constructed and arranged for advancing and closing movements, a shoe support, an abutment for the other end of the shoe, a power-operated cam for effecting relative movement of the wipers and support heightwise of the shoe to shape the upper to the last and into the angle between the side of the last and the projecting margin of the sole, and for pressing the abutment toward the shoe, said cam having a dwell, and power-operated means acting during the dwell of the cam to advance and close the wipers positively a predetermined amount to tuck the upper under the last bottom, while the shoe is held by said abutment, said cam acting after the wiper movements have occurred to apply heavy pressure to the outturned upper materials and the projecting margin of the sole.

46. In a machine for operating on the end portions of stitchdown shoes, the combination of a support to receive the sole of a shoe attached to its last and to support the sole including the margin thereof which projects beyond the last bottom, a wiper support above said shoe support, a pair of end embracing wipers on said wiper support constructed and arranged for advancing and closing movements, means for effecting relative movement heightwise of the shoe between the shoe support and the wipers to shape the upper to the last, means for forcing the shoe endwise toward the wipers during the shaping operation and power-operated means for effecting predetermined advancing and closing movements of the wipers and for applying heavy pressure to the shoe materials between the wipers and the sole support.

47. In a machine for operating on the end portions of stitchdown shoes, the combination of a support to receive the sole of a shoe attached to its last and to support the sole including the margin thereof which projects beyond the last bottom, a wiper support above said shoe support, a pair of end embracing wipers on said wiper support constructed and arranged for advancing and closing move-

ments, means for effecting relative movement heightwise of the shoe between the shoe support and the wipers to shape the upper to the last, means for forcing the shoe endwise toward the wipers during said shaping operation, and power-operated means for pressing the outturned flange of the upper against the projecting margin of the sole for advancing and closing the wipers a predetermined amount to tuck the upper into the angle between the side of the last and the projecting margin of the sole and for then applying further pressure to the materials between the wipers and the sole support.

48. In a machine for shaping the end portion of a stitchdown shoe to its last, the combination of a support to receive the sole of a shoe on its last, a pair of end embracing wipers constructed and arranged for advancing and closing movement, power-operated means for effecting relative movement heightwise of the shoe between the shoe support and the wipers to shape the upper to the last, an abutment for engaging the opposite end of the shoe and initially spaced therefrom to permit presentation of the shoe to the wipers, manually operated means for moving the abutment toward the wipers, means operated by said power-operated means for pressing the abutment endwise against the shoe during the operation of the wipers, and power-operated means for advancing and closing the wipers.

49. In a machine for shaping the end portion of a stitchdown shoe to its last, the combination of a support to receive the sole of a shoe on its last, a pair of end embracing wipers constructed and arranged for advancing and closing movement, power-operated means for effecting relative movement heightwise of the shoe between the shoe support and the wipers to shape the upper to the last, an abutment for engaging the opposite end of the shoe and initially spaced therefrom to permit presentation of the shoe to the wipers, manually operated means for moving the abutment toward the wipers, means operated by said power-operated means for pressing the abutment endwise against the shoe during the operation of the wipers, and power-operated means for advancing and closing the wipers and for exerting pressure upon the outturned flange of the upper between the wipers and the support.

50. In a machine for shaping the end portion of a stitchdown shoe to its last, the combination of a support to receive the sole of a shoe on its last and to support the sole including the margin of the sole which projects beyond the last bottom, a pair of end embracing wipers located above the support and constructed and arranged for advancing and closing movements, power-operated means for effecting relative movement heightwise of the shoe between the shoe support and the

wipers to shape the upper to the end of the last and against the projecting margin of the sole, an abutment for engaging the opposite end of the shoe and initially spaced therefrom, and manually operated means for moving the abutment toward the shoe and for setting the power means in operation, said power means then operating to force the abutment against the shoe and to effect advancing 10 and closing movements of the wipers while the shoe is held from endwise movement by said abutment.

51. In a machine for shaping the end portion of a stitchdown shoe upper to its last, the combination of a support to receive the sole of a shoe on its last, a pair of end embracing wipers above the support, means for effecting movement of the support toward the wipers to cause the wipers to shape the upper 20 to the end of the last, a slide carried by said support and arranged for movement longitudinally of the shoe, a carriage adjustable longitudinally of the slide, an abutment for the opposite end of the shoe mounted on said carriage and having a lost motion connection with the carriage, a spring for holding the carriage away from the shoe, means for moving the carriage against said spring to take up said lost motion, and means operated 25 during the movement of the support to apply pressure to the abutment and maintain the upper in wiping relation to the wipers during the upper shaping operation.

52. In a machine for shaping the end portion of a stitchdown shoe upper to its last, the combination of a support to receive the sole of a shoe on its last, a pair of end embracing wipers above the support, means for effecting movement of the support toward the 30 wipers to cause the wipers to shape the upper to the end of the last, a slide carried by said support and arranged for movement longitudinally of the shoe, a carriage adjustable longitudinally of the slide, an abutment for the opposite end of the shoe mounted on said carriage and having a lost motion connection with the carriage, a spring for holding the carriage away from the shoe, means for moving the carriage against said spring to take up 35 said lost motion, and means operated as an incident to the movement of the support to press the slide toward the wipers and to apply pressure to the abutment to maintain the upper in wiping relation to the wipers during the upper shaping operation, said spring acting when the shoe is released from the machine to move the carriage and abutment away from the shoe to permit removal of the shoe.

53. In a machine for shaping the end portion of a stitchdown shoe upper to its last, the combination of a support to receive the sole of a shoe on its last, a wiper support above said shoe support, a pair of end embracing wipers on the wiper support, means 40 for effecting movement of the shoe support

toward the wipers to cause the wipers to shape the upper to the toe of the last, a slide carried by said support and arranged for movement longitudinally of the shoe, a carriage adjustable relatively to the slide, an abutment for the opposite rear end of the shoe mounted on said carriage and having a lost motion connection with the carriage, a spring for holding the slide away from the shoe, and means operating as an incident to said movement 45 of the support for moving the slide toward the wipers to apply pressure to the abutment to maintain the upper in holding relation to the wipers during the upper shaping operation, said spring acting to return the slide to initial position, the abutment being then, because of said lost motion connection, spaced from the shoe to permit easy removal thereof.

54. In a machine for shaping the end portion of a stitchdown shoe to its last, the combination of a support to receive the sole of a shoe on its last, a pair of end embracing wipers above the support, means for effecting relative movement between the support and wipers to cause the wipers to shape the upper 50 to the end of the last, a slide carried by said support and arranged for movement longitudinally of the shoe, a carriage adjustable longitudinally of the slide, an abutment for the opposite end of the shoe mounted on said carriage and having a lost motion connection with the carriage, said carriage and abutment being so constructed and arranged that the carriage may be adjusted on the slide only when the abutment is positioned toward the shoe at the limit of its lost motion, means for moving the carriage to take up said lost motion, and means for operating the slide to cause the abutment to be pressed against the shoe to hold the upper in wiping relation to the wipers during the shaping operation.

55. In a machine for shaping the end portion of a stitchdown shoe to its last, the combination of a support to receive the sole of a shoe on its last, a pair of end embracing wipers above the support, means for effecting relative movement between the support and wipers to cause the wipers to shape the upper to the end of the last, a slide carried by said support and arranged for movement longitudinally of the shoe, a carriage adjustable longitudinally of the slide, a lock for holding the carriage to the slide, an abutment for the opposite end of the shoe having a stem movable longitudinally of the shoe in said carriage, said stem and lock being so constructed and arranged that the stem prevents release of the lock when the abutment is in its rearward position and permits release of the lock when in its forward position, means for moving the carriage toward the shoe to cause the stem to lock the slide, and means to apply pressure to the carriage to maintain the abutment against the end of the shoe to hold the 100

upper in wiping relation to the wipers during the upper shaping operation.

56. In a machine for shaping the toe portion of a stitchdown shoe upper to its last, the combination of a support to receive the sole of a shoe on its last and to support the sole including a projecting margin thereof, end embracing means above said support, means for effecting relative movement heightwise of the shoe between the shoe support and the end embracing means, and means for clamping the upper locally at the two sides of the toe, said means acting in opposition to the lower face of said end embracing means to clamp the upper during said relative heightwise movement.

57. In a machine for shaping the toe portion of a stitchdown shoe upper to its last, the combination of a support to receive the sole of a shoe on its last and to support the sole including a projecting margin thereof, a wiper support above said shoe support, a pair of end embracing wipers on said support, means for effecting relative movement heightwise of the shoe between the shoe support and the wipers, and means engaging the upper at the sides only of the toe, said means cooperating with the wipers to clamp the upper during said relative heightwise movement.

58. In a machine for shaping the toe portion of a stitchdown shoe upper to its last, the combination of a support to receive the sole of a shoe on its last, a wiper support above said shoe support, a pair of end embracing wipers on said support, means for effecting relative movement heightwise of the shoe between the shoe support and the wipers to cause the upper to be wiped over the toe of the last, and means cooperating with the wipers to clamp the upper constructed and arranged to be operated during a part of the relative heightwise movement between the shoe support and the wipers and to be withdrawn from operative position during another part of said relative heightwise movement.

59. In a machine for operating on the toe portions of stitchdown shoes, the combination of end embracing wipers, a shoe support movable heightwise of the shoe relatively to the wipers, said support being constructed and arranged to support a projecting margin of a sole, clamps cooperating with the wipers to clamp the upper, means for moving the shoe support to effect shaping of the upper by the wipers over the toe of the last, means for moving the clamps to engage the upper before the movement of the shoe support is initiated, and means for withdrawing the clamp from operative position before movement of the support is completed so that the outturned margin of the upper and the projecting margin of the sole may be pressed together between the wipers and the support.

60. In a machine for operating on the toe portions of stitchdown shoes, the combination of end embracing wipers, a shoe support movable heightwise of the shoe relatively to the wipers, clamps cooperating with the wipers to clamp the upper, means for moving the shoe support to effect shaping of the upper by the wipers over the toe of the last, and means for causing the clamping pressure of the clamps to increase as the shoe support is moved.

61. In a machine for operating on the toe portions of stitchdown shoes, the combination of end embracing wipers, a shoe support movable heightwise of the shoe relatively to the wipers, clamps cooperating with the wipers to clamp the upper, means for moving the clamps into clamping position, means for moving the shoe support to effect shaping of the upper by the wipers over the toe of the last, and connections between the clamps and shoe support to cause the clamping pressure of the clamps upon the upper to increase during the movement of the shoe support.

62. In a machine for operating on the toe portions of stitchdown shoes, the combination of end embracing wipers, clamps cooperating with the wipers to clamp the upper, a shoe support, means for effecting relative movement heightwise of the shoe between the shoe support and the wipers to effect shaping of the upper by the wipers over the toe of the last, means for withdrawing the clamps outwardly of the shoe progressively during the upward movement of the shoe support, and means to cause the clamping pressure of the clamps upon the upper to progressively increase during the progressive withdrawal of the clamps.

63. In a machine for operating on the toe portions of stitchdown shoes, the combination of end embracing wipers, a shoe support movable heightwise of the shoe relatively to the wipers, clamps cooperating with the lower faces of the wipers to clamp the upper, means for moving the shoe support to effect shaping of the upper by the wipers over the toe of the last, means for withdrawing the clamps outwardly of the shoe progressively during the upward movement of the shoe support, and connections between the clamps and the shoe support to cause the clamping pressure of the clamps upon the upper to progressively increase during the progressive withdrawal of the clamps.

64. In a machine for operating on the toe portions of stitchdown shoes, the combination of end embracing wipers, a shoe support movable heightwise of the shoe relatively to the wipers, clamps cooperating with the wipers to clamp the upper, manually operated means for effecting preliminary movement of the clamps into clamping position, power-operated means for moving the shoe support to effect shaping of the upper over the toe of the

shoe, and means operated by said power means to produce an effective clamping pressure between the clamps and the wipers.

65. In a machine for shaping the toe portion of stitchdown shoe uppers, the combination of a pair of end embracing wipers, a shoe support to receive the forepart of the bottom of a shoe to be lasted, said support being adapted to support a sole attached to a last including the margin thereof which extends beyond the edge of the last, clamps for holding the upper against the wipers, means for effecting relative movement between the wipers and the shoe support heightwise of the shoe to cause the upper to be wiped over the toe of the last, and means operating in conjunction with said relative heightwise movement to operate the clamps to hold the upper yieldingly against the wipers to assist the wipers in shaping the upper to the toe of the last and into the angle between the side of the last and the projecting margin of the sole.

66. In a machine for shaping the toe portion of a stitchdown shoe upper to its last, the combination of a support to receive the sole of a shoe on its last, a pair of end embracing wipers, means for clamping the upper against the wipers, said means being initially spaced from the wipers to permit introduction of the upper between them, manually operated means for moving the clamping means to press the upper against the wipers, and power-operated means arranged to be set in operation after the clamping means has been pressed against the wipers for effecting relative heightwise movement between the support and the wipers to shape the upper to the toe of the last and to operate the clamping means to hold the upper frictionally against the lower face of the wipers.

67. In a machine for shaping the toe portion of a stitchdown shoe upper to its last, the combination of a support to receive the sole of a shoe on its last, a pair of end embracing wipers, means cooperating with the wipers to clamp the upper, means for effecting relative movement between the wipers and the support heightwise of the shoe to shape the upper to the toe of the last while drawing the upper under tension from the clamping means, and means for withdrawing the clamping means out of upper clamping position.

68. In a machine for shaping the toe portion of a stitchdown shoe upper, the combination of end embracing wipers, a shoe support constructed and arranged to receive the bottom of a shoe and to support the sole and shoe including the projecting margin of the sole, means cooperating with the wipers to clamp the upper, means for effecting relative movement between the wipers and the support heightwise of the shoe to shape the upper to the last, to apply pressure to the out-

turned upper and the projecting margin of the sole, and means for withdrawing the clamping means out of upper clamping position during the relative movement of the support and the wipers. 70

69. In a machine for shaping the toe portion of a stitchdown shoe upper, the combination of end embracing wipers, a shoe support constructed and arranged to receive the bottom of a shoe and to support the sole and shoe including the projecting margin of the sole, means cooperating with the wipers to clamp the upper, means for effecting relative movement between the wipers and the support heightwise of the shoe to shape the upper to the last, means operated by said relative movement between the wipers and support for withdrawing the clamping means out of upper clamping position and means for pressing the outturned margin of the upper and the projecting margin of the sole between the shoe support and the wipers. 80

70. In a machine for shaping the toe portion of a stitchdown shoe upper to its last, the combination of a support to receive the sole of a shoe on its last, a pair of end embracing wipers, power-operated means for effecting relative movement heightwise of the shoe between the shoe support and wipers, clamps for clamping the upper, said clamps being initially widely spaced apart to permit introduction of the shoe upper, manually operated means for bringing the clamps into position to engage the upper, means operating during said relative heightwise movement between the shoe support and wipers for operating the clamps to clamp the upper, and means operating during said relative heightwise movement for moving the clamps into inoperative position. 90

71. In a machine for shaping the toe portion of a stitchdown shoe to its last, the combination of a support to receive the sole of a shoe on its last, a pair of end embracing wipers, means cooperating with the wipers to clamp the upper, manually operated means for effecting initial movement of the clamping means into clamping position, power-operated means for effecting relative movement heightwise of the shoe between the shoe support and the wipers to shape the upper to the toe of the last and for operating the clamping means frictionally to hold the upper against the wipers, and power-operated means for withdrawing the clamping means from operative position and for exerting pressure upon the outturned flange of the upper and the margin of the sole between the wipers and the support. 100

72. In a machine for operating on the toe portion of a stitchdown shoe upper, the combination of end embracing wipers, a shoe support constructed and arranged to receive the bottom of a shoe presented right side up to the wipers and to support the sole and shoe 110

including the projecting margin of the sole, means for cooperating with the under side of the wipers to clamp the upper, means for effecting relative movement of the wipers 5 and the support heightwise of the shoe to shape the upper to the toe of the last while drawing the upper under tension from the clamping means, and means for withdrawing the clamping means out of upper clamping 10 position.

73. In a machine for shaping the toe portion of a stitchdown shoe to its last, the combination of end embracing wipers, a shoe support constructed and arranged to receive the 15 bottom of a shoe presented right side up to the wipers and to support the sole and shoe including the projecting margin of the sole, means for clamping the upper against the under side of the wipers and over the projecting margin of the sole, means to effect relative movement between the wipers and the support heightwise of the shoe to shape the upper to the toe of the last while drawing the upper under tension from the clamping 20 means and to press the outturned upper against the projecting margin of the sole, and means for moving the clamping means outwardly of the last during said relative heightwise wiping movement to permit the 25 outturned margin of the upper and the projecting margin of the sole to be pressed between the wipers and the support.

74. In a machine for shaping the toe portion of a stitchdown shoe upper to its last, the combination of end embracing wipers, a shoe support constructed and arranged to receive the bottom of a shoe presented right side up to the wipers and to support the sole and shoe including the projecting margin of 30 the sole, means movable toward the under side of the wipers to clamp the upper, means to effect relative movement between the wipers and the support heightwise of the shoe to shape the upper to the toe of the last while drawing the upper under tension from the clamping means, and means acting during 35 said shaping operation for moving the clamping means in a plane substantially parallel to the plane of the last bottom out of upper clamping position.

75. In a machine for shaping the toe portion of a stitchdown shoe to its last, the combination of a support to receive the sole of a shoe on its last, a pair of end embracing 40 wipers, means for clamping the upper at the sides of the toe against the wipers, means for effecting relative movement heightwise of the shoe between the shoe support and the wipers to shape the upper to the toe of the last and to operate the clamping means to hold the upper frictionally against the lower face of the wipers.

76. In a machine for shaping the toe portion of a stitchdown shoe upper to its last, the combination of a support to receive the sole of 45

a shoe on its last, a pair of end embracing wipers, clamps arranged at the sides and corners of the toe for clamping the upper against the wipers, said clamps having corrugations extending transversely of their upper engaging faces, and means for effecting relative movement between the shoe support and the wipers heightwise of the shoe to shape the upper to the toe of the last and to operate the clamps to hold the upper against the wipers, the corrugated faces of the clamps acting to retard movement of the upper between the clamps and the wipers as the shaping operation progresses.

77. In a machine for lasting stitchdown shoes, the combination of a support to receive the sole of a shoe attached to its last, a wiper support above said shoe support, a pair of end embracing wipers on said support, means for effecting relative movement heightwise of the shoe between the shoe support and the wipers, means cooperating with the wipers to clamp the upper at the sides of the toe, said clamping means being constructed and arranged to be operated during the relative heightwise movement between the shoe support and the wipers, and means for withdrawing the clamping means from operative position during the relative heightwise movement between the support and wipers.

78. In a machine for lasting stitchdown shoes, the combination of a support to receive the sole of a shoe on its last, a wiper support above said shoe support, a pair of end embracing wipers on said support, means for effecting relative movement heightwise of the shoe between the shoe support and the wipers, upper clamps arranged at the corners of the toe and at the sides of the toe for movement to clamp the upper against the lower face of the wipers, means operating during said relative heightwise movement between the shoe support and wipers for operating the clamps to clamp the upper, and means constructed and arranged to be brought into operation toward the end of said relative heightwise movement between the wipers and the support for moving the corner clamps longitudinally of the shoe away from the shoe and for swinging the side clamps into 105 inoperative position.

79. In a machine for lasting the toe portions of stitchdown shoes, the combination of a pair of end embracing wipers, a shoe support to receive the forepart of the bottom of a shoe to be lasted, said support being adapted to support a sole attached to a last including the margin thereof which extends beyond the sides of the last, means for effecting relative movement heightwise of the shoe between the shoe support and the wipers, clamps arranged at the sides and corners of the toe and extending over the projecting margin of the sole into proximity to the last, means for operating the clamps to clamp the 110 115 120 125 130

upper against the wipers during said relative heightwise movement between the shoe support and the wipers, and power-operated means for withdrawing the corner clamps longitudinally of the shoe and the side clamps laterally of the shoe out of position over the sole and for exerting heavy pressure upon the outturned flange of the upper and the margin of the sole between the wipers and the support.

80. In a machine for lasting stitchdown shoes, the combination of a support to receive the sole of a shoe attached to its last, a wiper support above said shoe support, a pair of end embracing wipers on said wiper support, means for effecting relative movement heightwise of the shoe between the shoe support and the wipers, means movable toward the lower face of the wipers to clamp the upper, an abutment engaging the opposite end of the shoe to hold the shoe against the wipers during the operation of the wipers, and means constructed and arranged to move the abutment toward the shoe during said relative heightwise movement.

81. In a machine for lasting stitchdown shoes, the combination of a support to receive the sole of a shoe attached to its last, a wiper support above said shoe support, a pair of end embracing wipers on said support, means for effecting relative movement heightwise of the shoe between the shoe support and the wipers, means cooperating with the lower face of the wipers to clamp the upper, means engaging the opposite end of the shoe to hold the shoe endwise against the wipers, and means operated in conjunction with said relative heightwise movement to cause the abutment to engage the shoe.

82. In a machine for lasting stitchdown shoes, the combination of a support to receive the sole of a shoe attached to its last, a wiper support above said shoe support, a pair of end embracing wipers on said support, means for effecting relative movement heightwise of the shoe between the shoe support and the wipers, means cooperating with the lower face of the wipers to clamp the upper, and means acting automatically to apply pressure to the rear end of the shoe to urge the shoe toward the wipers during the relative movement between the shoe support and the wipers.

83. In a machine for shaping the end of a stitchdown shoe to its last, the combination of wipers, a shoe support, means for effecting relative movement of the wipers and the support heightwise of the shoe, means for clamping the outwardly projecting margin of the upper against the wipers, and means operating in conjunction with said relative movement and without attention on the part of the operator for pressing the shoe endwise against the wipers.

84. In a machine for lasting stitchdown

shoes, the combination of a support to receive the sole of a shoe attached to its last, a wiper support above said shoe support, a pair of end embracing wipers on said support, means for effecting relative movement heightwise of the shoe between the shoe support and the wipers, means cooperating with the lower face of the wipers to clamp the upper, an abutment for the rear end of the shoe, and means for urging the abutment yieldingly toward the wipers during the relative movement between the shoe support and the wipers.

85. In a machine for shaping the toe portion of a stitchdown shoe upper to its last, the combination of a support to receive the sole of a shoe on its last, a pair of end embracing wipers, and power operated means for effecting relative movement heightwise of the shoe between the shoe support and wipers, for clamping the upper against the wipers, and for pressing the shoe endwise toward the wipers during the operation of the wipers.

86. In a machine for shaping the end portion of a stitchdown shoe to its last, the combination of end embracing wipers constructed and arranged for advancing and closing movements, a shoe support constructed and arranged to support the shoe including a projecting margin of a sole, means for effecting relative movement of the support and wipers heightwise of the shoe, means for clamping the outwardly projecting margin of the upper against the wipers during the relative movement between the wipers and the support, and power-operated means for advancing and closing the wipers at the termination of said relative movement between the support and the wipers and for pressing together the outturned margin of the upper and the projecting margin of the sole.

87. In a machine for shaping the end portion of a stitchdown shoe to its last and to the margin of a sole projecting beyond the last bottom, the combination of end embracing wipers constructed and arranged for advancing and closing movements, a shoe support, means for effecting relative movement of the support and wipers heightwise of the shoe, to crease the upper at the angle between the side of the last and the projecting margin of the sole, means cooperating with the wipers for clamping the outwardly projecting margin of the upper during the relative movement between the wipers and the support, means for withdrawing the clamping means from operative position, and means for advancing and closing the wipers to cause the crease in the upper to extend under the last bottom.

88. In a machine for lasting the toes of stitchdown shoes, the combination of a pair of wipers constructed and arranged to advance and close, a shoe support to receive the

forepart of the bottom of a shoe to be lasted, said support being adapted to support a sole attached to a last including the margin thereof which extends beyond the sides of the last, means under control of the operator for effecting relative movement between the wipers and the shoe support heightwise of the shoe to cause the upper to be wiped over the toe of the last toward the sole, clamping members operating in conjunction with said relative heightwise movement to clamp the upper yieldingly against the wipers to assist the wipers in shaping the upper to the toe of the last and into the angle between the side of the last and the projecting margin of the sole, means for effecting advancing and closing movements of the wipers after the termination of said relative heightwise movement, and means for applying pressure between the wipers and the support to the projecting margins of the sole and upper.

89. In a machine for lasting stitchdown shoes, the combination of a shoe support to receive the sole of a shoe attached to its last and to support the sole including the margin of the sole which projects beyond the last bottom, a wiper support above said shoe support, a pair of end embracing wipers mounted on the wiper support for advancing and closing movements relatively to the toe of the shoe located on the support, means for adjusting the opening of the wipers to correspond to the shape of the toe being operated upon, manually operated means for effecting relative heightwise movement of the shoe support and wipers while the wipers remain in initial position as to advancing and closing movements, means constructed and arranged to exert pressure on the rear end of the shoe yieldingly to hold the shoe against the wipers so that the wipers will shape the upper to the ends of the last and against the projecting margin of the sole, and power-operated means arranged for operation only after such relative heightwise wiping movement has taken place to cause the wipers to tuck the upper under the shoe bottom between the side of the last and the projecting margin of the sole.

90. In a machine for lasting the toes of stitchdown shoes, the combination of a pair of wipers constructed and arranged to advance and close, a shoe support to receive the forepart of the bottom of a shoe to be lasted, said support being adapted to support a sole attached to a last including the margin thereof which extends beyond the sides of the last, means under control of the operator for effecting relative movement between the wipers and the shoe support heightwise of the shoe to cause the upper to be wiped over the toe of the last toward the sole, means for frictionally holding the margin of the upper to assist the wipers in shaping the upper to the toe of the last and into the angle

between the side of the last and the projecting margin of the sole, and power-operated means for effecting advancing and closing movements of the wipers at the termination of said relative heightwise movement and for applying pressure between the wipers and the support to the projecting margins of the sole and upper.

91. In a machine for shaping the end portion of a stitchdown shoe to its last, the combination of end embracing means, a shoe support to receive the shoe and last and to support the shoe sole including its projecting marginal portion, means for effecting relative movement of the end embracing means and the shoe support heightwise of the shoe to shape the upper about the last and press its marginal portion against the projecting margin of the sole, and means operating during said relative movement to press the shoe upper against the last in the vicinity of the tip line.

92. In a machine for shaping the end portion of a stitchdown shoe to its last, the combination of end embracing means, a shoe support to receive the sole of the shoe, means for effecting relative movement between the end embracing means and the shoe support heightwise of the shoe to shape the upper to the last, and means cooperating with the shoe support during said relative movement to press the shoe upper against the last in the vicinity of the tip line to prevent the shaping action of the end embracing means from bowing the tip seam.

93. In a machine for lasting the toe portion of a stitchdown shoe, the combination of end embracing wipers, a shoe support constructed and arranged to receive the bottom of a shoe presented right side up to the wipers and to support the sole of the shoe including the projecting margin of the sole, means for effecting movement of the support heightwise of the shoe toward the wipers to shape the upper to the toe of the last, and means for preventing the upper shaping action of the wipers from bowing the tip seam.

94. In a machine for lasting the toe portion of a stitchdown shoe, the combination of end embracing wipers, a shoe support constructed and arranged to receive the bottom of a shoe presented right side up to the wipers and to support the sole of the shoe including the projecting margin of the sole, means for effecting movement of the support heightwise of the shoe toward the wipers to shape the upper to the toe of the last, and a yielding pad constructed and arranged to be encountered by the toe portion of the upper during said heightwise movement of the support and to hold the upper pressed against the last whereby movement of the upper relatively to the last is prevented during the operation of shaping the upper to the toe of the last.

95. In a machine for lasting the toe por-

tion of a stitchdown shoe, the combination of end embracing wipers, a shoe support constructed and arranged to receive the bottom of a shoe presented right side up to the
5 wipers and to support the sole of the shoe including the projecting margin of the sole, means for effecting movement of the support heightwise of the shoe toward the wipers to shape the upper to the toe of the last, and a
10 yielding pad by which the toe portion of the upper is pressed against the last during said heightwise movement of the support.

In testimony whereof I have signed my name to this specification.

15

WILLIAM C. BAXTER.
